CLAIM

The ornamental design for an automobile front bumper, as shown and described.

DESCRIPTION

1. Automobile front bumper

1.1 is a front and left side perspective view of an automobile front bumper showing our new design;

1.2 is a front elevation view thereof;

1.3 is a rear elevation view thereof;

1.4 is a right side elevation view thereof;

1.5 is a left side elevation view thereof;

1.6 is a top plan view thereof; and

1.7 is a bottom plan view thereof.
